UNITED STATES PATENT OFFICE

2,650,328

CIRCUIT CONTROL DEVICE

Homer B. James, Lima, Ohio, assignor to Westinghouse Electric Corporation, East Pittsburgh, Pa., a corporation of Pennsylvania

Application November 16, 1950, Serial No. 196,041

7 Claims. (Cl. 317—37)

1

My invention relates, generally, to circuit breaker control systems and, more particularly, to systems for controlling the operation of electromagnetically operated circuit breakers or contactors.

An object of my invention, generally stated, is to provide for controlling the operation of a reliable and compact contactor in a simple and efficient manner.

A more specific object of my invention is to provide for obtaining both a time delay opening of a contactor in response to normal overloads and a substantially instantaneous opening in response to abnormally high currents.

Another object of my invention is to provide for controlling the opening of a circuit breaker or contactor by combined thermal and magnetic means.

A further object of my invention is to utilize a thermally responsive bimetal tripping member to energize a magnetic tripping means for a circuit breaker or contactor.

Still another object of my invention is to provide for readily adjusting the tripping mechanism of a contactor.

Other objects of my invention will be explained fully hereinafter or will be apparent to those skilled in the art.

In practicing my invention, a main contactor, a combined thermal and magnetic tripping means, a control switch and trip resistors are mounted on a common base. The operation of the contactor may be manually controlled by means of a switch located remotely from the unit assembly. Delayed tripping on normal overloads is obtained by means of a U-shaped thermally responsive bimetal which also functions as a one-turn coil to energize a magnet by the load current, thereby obtaining instantaneous tripping on abnormally high currents.

For a better understanding of the nature and objects of the invention, reference may be had to the following detailed description, taken in conjunction with the accompanying drawings, in which:

Figure 1 is a view, in top plan, of a contactor and control unit assembly embodying the principal features of the invention, the cover for the unit being removed;

Fig. 2 is a view, partly in side elevation and partly in section, of the unit shown in Fig. 1;

Fig. 3 is a view, in section, taken along the line III—III of Fig. 1;

Fig. 4 is a view, in bottom plan, of the unit shown in Fig. 1;

2

Fig. 5 is a view, in section, taken along the line V—V of Fig. 4;

Fig. 6 is an enlarged detail view, in section, taken along the line VI—VI of Fig. 4; and

Fig. 7 is a diagrammatic view showing the control circuit connections for the contactor and its associated apparatus.

Referring to the drawings, the structure shown therein comprises an insulating base 10 upon which is mounted an electromagnetic contactor 11, a control switch 12 and a pair of resistors 13. A recess 14 is provided in the bottom side of the base 10 in which is mounted a bimetal plate 15, and an electromagnet 16 having an armature 17.

As shown most clearly in Fig. 2, a cover 18 may be attached to the base 10 by means of screws 19 which are threaded into brackets 21 on the cover 18. The cover 18 protects the contactor 11, the control switch 12 and the resistors 13. As shown in Fig. 3, a cover plate 22 may be attached to the bottom of the base 10 to protect the bimetal plate 15, the electromagnet 16 and the armature 17.

As shown most clearly in Fig. 3, the contactor 11 comprises a U-shaped frame 23, a coil 24, a fixed core 25 which is attached to the frame 23 by a screw 26 and a movable core 27 which is disposed inside of a sleeve 28 on which the coil 24 is mounted. Contact bars 29 and 31 (see Fig. 1) are attached to an insulating member 32 which in turn, is attached to one end of the frame 23 by means of a metal plate 33 and screws 34.

A bridging contact member 35 is disposed to engage contact members 36 and 37 mounted on the contact bars 29 and 31, respectively. An arcing contact member 38 is disposed to bridge contact members 39 and 41 also mounted on the contact bars 29 and 31, respectively.

As shown most clearly in Fig. 3, the bridging contact member 35 and the arcing contact member 38 are carried by the movable core 27. A compression spring 42 is disposed between the insulating member 32 and the bridging contact member 35. Another compression spring 43 is disposed between the arcing contact member 38 and a cup washer 44 attached to the end of the core 27. A guide bar 45 is disposed to guide the movement of the bridging member 35 and the arcing contact member 38 as the core 27 is actuated toward the core 25 when the coil 24 is energized, thereby closing the bridging contact members and the arcing contact members.

The control switch 12 may be of a standard construction and is a single pole, double throw

switch having a snap action with automatic return. The control switch may be attached to the base 10 by means of a U-shaped bracket 46 and screws 47. As shown most clearly in Fig. 5, the control switch has an actuating plunger 48 to which is attached an extension cap 49. Terminal members 51, 52 and 53 are provided on the control switch 12 for making the necessary electrical connections.

The resistors 13 are also of a standard construction. Terminal members 54 are provided on the resistors for making electrical connections to the resistors. Main contact studs 55 and 56 are provided for making the main circuit connections to the control unit. Secondary contact studs 57 and 58 are provided for making the control connections to the unit.

As explained hereinbefore, our invention provides for obtaining a time delay operation of the contactor 11 in response to normal overloads in the circuit controlled by the contactor and an instantaneous tripping characteristic in response to abnormally high currents. The time delay action is of a thermal nature utilizing the bimetal plate 15 which is of a U-shape.

The ends of the U-shaped bimetal are rigidly attached to the base 10 by screws 61, and the bimetal is electrically connected in series with the main circuit which is controlled by the contactor 11. The remainder of the bimetal plate 15 is mechanically free and will deflect a certain amount corresponding to the temperature rise in the bimetal, which rise in temperature takes place when there is an increase in the amount of the current flowing in the power circuit and through the bimetal plate. The free end of the bimetal 15 is provided with an adjustable screw 62 which is disposed to engage the lower end of the extension cap 49 on the plunger 48 for the control switch 12.

The instantaneous tripping action is obtained by means of the electromagnet 16 in combination with the bimetal plate 15. The electromagnet 16 comprises pole pieces 63 and 64 which are attached to the base 10 by brackets 65 and 66, respectively, and a yoke 67 which bridges the pole pieces 63 and 64, thereby forming a magnet of a horseshoe type.

As shown in Fig. 4, the pole piece 64 of the magnet 16 is disposed between the two legs of the bimetal plate 15 and is substantially surrounded by the bimetal plate. The other pole piece 63 is at one outside edge of the bimetal plate. Thus, the magnet 16 is energized by the load current flowing in the bimetal plate since this plate functions as a one-turn coil around the pole piece 64 of the magnet. The armature 17 for the electromagnet 16 is mounted on the opposite side of the bimetal plate 15 and abuts against the two pole pieces 63 and 64 when actuated.

As shown, the armature 17 is of a T-shape with the top 68 of the T bridging the pole pieces 63 and 64. The leg 69 of the armature is so mounted in a bracket 71 by means of pivot pins 72 that the armature is dynamically balanced. An adjustable screw 73 is provided for adjusting the normal position of the armature 17.

A hole 74 is provided near the end of the leg 69 of the armature. As shown most clearly in Fig. 5, the lower end of the extension cap 49 on the plunger 48 for the control switch 12 extends through the hole 74, and the cap 49 is provided with a flange 75 which is engaged by the leg 69 of the armature. Thus, the plunger 48 of the control switch may be actuated by the armature

17 in response to the energization of the magnet 16 or by the bimetal plate 15 in response to the heating of the bimetal by the load current.

As shown in Fig. 6, the armature 17 is so biased by a spring 76 that the armature will not move and operate the control switch until the current through the bimetal is sufficient to overcome the force of the biasing spring 76, as well as a spring 77 (Fig. 7) in the control switch 12. The force of the spring 76 may be adjusted by means of a screw 78 which is threaded through an insert 79 in the base 10. The spring 76 may be adjusted to correspond to a predetermined amount of current, thereby eliminating nuisance tripping by currents below the predetermined amount.

A holding coil 81 is disposed on the pole piece 63 of the electromagnet 16. The holding coil 81 is designed to actuate the armature 17 against the pole pieces 63 and 64 or hold it against the pole pieces once it has been actuated into engagement with the pole pieces by the load current flowing through the bimetal 15 in the manner hereinbefore explained.

As shown in Fig. 7, a switch 82 which is manually operable to open and close its contacts is located remotely from the control unit assembly. The switch 82 is preferably a thermal circuit breaker having a thermally operated tripping mechanism comprising a bimetal 83 which bridges contact members 84 and 85 when a handle 80 is actuated to the closed position. Thus, when a predetermined current flows through the bimetal 83, it is actuated to interrupt the circuit through the contact members 84 and 85.

Referring to Fig. 7, it will be seen that upon bridging the contact members 84 and 85 of the circuit breaker 82, a circuit extends from positive through the contact members 84 and 85, conductor 86, contact members 87 and 88 of the control switch 12, a conductor 89, the actuating coil 24 of the contactor 11 and conductor 91 to ground. The energization of the coil 24 closes the contact members of the contactor 11, thereby connecting the bimetal plate 15 in series-circuit relation with the load circuit which is connected to the terminals 55 and 56.

Upon any fault or overload condition sufficient to actuate the bimetal plate 15 or the armature 17 as hereinbefore described, the contact member 87 of the control switch 12 is disengaged from the contact member 88 and engages a contact member 92. This operation of the control switch 12 deenergizes the coil 24 of the contactor 11, thereby opening the circuit through the contact members of the contactor and energizing the holding coil 81 on the electromagnet 16. A circuit is also established through the resistors 13.

As explained hereinbefore, the holding coil 81 energizes the electromagnet 16 to actuate the armature 17, thereby retaining the contact member 87 of the control switch 12 in engagement with the contact member 92 until the bimetal 83 trips the circuit breaker 82, thereby opening the control circuit. The resistors 13 are connected in the control circuit to increase the current flowing through the bimetal 83, thereby tripping the circuit breaker 82 and permitting the handle 80 to return to the open position.

When the control circuit is deenergized by the opening of the circuit breaker 82, the holding coil 81 is deenergized, and the armature 17 and the control switch 12 return to their normal positions. However, the contactor 11 can be reclosed only by manually reclosing the circuit breaker 82. Thus, the tripping of the contactor 11 is

automatically controlled by the overload protective devices, and the reclosing of the contactor is remotely controlled by a manually operable switch or circuit breaker.

From the foregoing description, it is apparent that we have provided both a time delay and an instantaneous tripping scheme for controlling the operation of an electromagnetic contactor. The tripping devices may be readily adjusted to secure the desired operating characteristics, and the apparatus required is light in weight and may be compactly assembled, thereby being advantageous for utilization in aircraft. There is no time lag in the operation of the instantaneous tripping upon abnormal overloads because of the minimum inductance of the one-turn coil provided by the bimetal plate 15. A minimum number of mechanical parts in the system precludes maloperation from friction and other mechanical difficulties.

Since numerous changes may be made in the above-described construction, and different embodiments of the invention may be made without departing from the spirit and scope thereof, it is intended that all matter contained in the foregoing description or shown in the accompanying drawings shall be interpreted as illustrative and not in a limiting sense.

I claim as my invention:

1. A control device comprising a contactor for controlling a load circuit, said contactor having an operating coil, a control switch connected to the operating coil for controlling the energization of said coil, a bimetallic element connected in series in the load circuit to carry the load current, said bimetallic element being disposed to engage the control switch to actuate said switch to effect deenergization of said coil in response to overload current in the load circuit, and electromagnetic means disposed to independently engage the control switch to effect actuation of the control switch, said electromagnetic means including a magnetic circuit, and the bimetallic element being disposed to at least partially encircle the magnetic circuit, whereby the electromagnetic means is energized by the load current flowing through the bimetallic element.

2. A control device comprising a contactor for controlling a load circuit, said contactor having an operating coil, a control switch connected to the operating coil for controlling the energization of said coil, a bimetallic element connected in series in the load circuit to carry the load current, said bimetallic element being generally U-shaped and being disposed to engage the control switch to actuate said switch to effect deenergization of said coil in response to overload current in the load circuit, and electromagnetic means disposed to independently engage the control switch to effect actuation of the control switch, said electromagnetic means including a magnetic circuit disposed between the legs of the U-shaped bimetallic element to be energized by the current flowing in the bimetallic element, the electromagnetic means being adapted to effect substantially instantaneous actuation of the control switch in response to overload current in excess of a predetermined value in the load circuit.

3. A control device comprising a contactor for controlling a load circuit, said contactor having an operating coil, a control switch connected to the operating coil for controlling the energization of said coil, a bimetallic element connected in series in the load circuit to carry the load cur-

rent, said bimetallic element being generally U-shaped and being disposed to engage the control switch to actuate said switch to effect deenergization of said coil in response to overload current in the load circuit, and electromagnetic means disposed to independently engage the control switch to effect actuation of the control switch, said electromagnetic means including a magnetic circuit disposed between the legs of the U-shaped bimetallic element to be energized by the current flowing in the bimetallic element, the electromagnetic means being adapted to effect substantially instantaneous actuation of the control switch in response to overload current in excess of a predetermined value in the load circuit, the electromagnetic means including a holding coil adapted to be energized by actuation of the control switch to maintain the control switch in actuated position.

20 4. A control device comprising a contactor for controlling a load circuit, said contactor having an operating coil, a control switch connected to the operating coil for controlling the energization of said coil, means for connecting the control switch to an external control conductor to establish an energizing circuit for the coil, a bimetallic element connected in series in the load circuit to carry the load current, said bimetallic element being disposed to engage the control switch to actuate said control switch in response to overload current in the load circuit to cause the control switch to effect deenergization of said coil, an alternative circuit adapted to be connected to said control conductor, means for completing said alternative circuit when the control switch is actuated, and electromagnetic means for independently effecting actuation of the control switch, said electromagnetic means including a magnetic circuit, and the bimetallic element being disposed to at least partially encircle the magnetic circuit, whereby the electromagnetic means is energized by the current flowing in the load circuit.

45 5. A control device comprising a contactor for controlling a load circuit, said contactor having an operating coil, a control switch connected to the operating coil for controlling the energization of said coil, means for connecting the control switch to an external control conductor to establish an energizing circuit for the coil, a bimetallic element connected in series in the load circuit to carry the load current, said bimetallic element being disposed to engage the control switch to actuate said control switch in response to overload current in the load circuit to cause the control switch to effect deenergization of said coil, an alternative circuit adapted to be connected to said control conductor, means for completing said alternative circuit when the control switch is actuated, and electromagnetic means for independently effecting actuation of the control switch, said electromagnetic means including a magnetic circuit, and the bimetallic element being disposed to at least partially encircle the magnetic circuit, whereby the electromagnetic means is energized by the current flowing in the load circuit, said electromagnetic means including a holding coil energized from said alternative circuit to maintain the control switch in actuated position.

70 6. A control device comprising a contactor for controlling a load circuit, said contactor having an operating coil, a control switch connected to the operating coil for controlling the

energization of said coil, means for connecting the control switch to an external control conductor to establish an energizing circuit for the coil, a generally U-shaped bimetallic element connected in series in the load circuit to carry the load current, said bimetallic element being disposed to engage the control switch to effect actuation of said control switch in response to overload current in the load circuit to cause the control switch to effect deenergization of said coil, an alternative circuit adapted to be connected to said control conductor, means for completing said alternative circuit when the control switch is actuated, and electromagnetic means including a magnetic circuit disposed between the legs of the U-shaped bimetallic element to be energized by the load current flowing in the bimetallic element, the electromagnetic means also including a movable armature adapted to independently actuate the control switch in response to overload current in the load circuit in excess of a predetermined value.

7. A control device comprising a contactor for controlling a load circuit, said contactor having an operating coil, a control switch connected to the operating coil for controlling the energization of said coil, means for connecting the control switch to an external control conductor to establish an energizing circuit for the coil, a generally U-shaped bimetallic element connected in series in the load circuit to carry the load current, said bimetallic element being disposed to

5 10 15

engage the control switch to effect actuation of said control switch in response to overload current in the load circuit to cause the control switch to effect deenergization of said coil, an alternative circuit adapted to be connected to said control conductor, means for completing said alternative circuit when the control switch is actuated, and electromagnetic means including a magnetic circuit disposed between the legs of the U-shaped bimetallic element to be energized by the load current flowing in the bimetallic element, the electromagnetic means also including a movable armature adapted to independently actuate the control switch in response to overload current in the load circuit in excess of a predetermined value, and a holding coil on said magnetic circuit, said holding coil being energized from said alternative circuit to maintain the control switch in actuated position.
